US00D505693S

(12) **United States Design Patent** (10) Patent No.: **US D505,693 S**
(45) Date of Patent: **** May 31, 2005**

(54) **HOPPER**

(75) Inventor: **Motoharu Kurosawa**, Iwatsuki (JP)

(73) Assignee: **Asahi Seiko Kabushiki Kaisha**, Tokyo (JP)

(**) Term: **14 Years**

(21) Appl. No.: **29/193,981**

(22) Filed: **Nov. 17, 2003**

(30) **Foreign Application Priority Data**

Jun. 30, 2003 (JP) 2003-018759

(51) LOC (7) Cl. **18-01**

(52) U.S. Cl. **D18/3.1; D99/34**

(58) Field of Search ..... D18/3.1, 12.1, D18/12.2, 12.3; D99/34, 35, 36, 37; 453/2, 3, 4, 9, 12, 13, 14, 15, 17, 30, 32, 34, 41, 44, 56-58, 61; 194/317, 334; 221/92; 232/4 R
